UNITED STATES PATENT OFFICE.

THOMAS CARL SPELLING, OF NEW YORK, N. Y.

TOY RAILROAD.

1,110,655.

Specification of Letters Patent. Patented Sept. 15, 1914.

Application filed June 8, 1914. Serial No. 843,766.

To all whom it may concern:

Be it known that I, THOMAS C. SPELLING, citizen of the United States, residing at New York, in the county of New York and State of New York, have invented certain new and useful Improvements in Toy Railroads, of which the following is a specification, reference being had therein to the accompanying drawing.

10 This invention relates to the art of tops, and educational appliances, and more particularly to toy railroads of that general character disclosed in my Letters Patent No. 1089799 dated March 10, 1914, and wherein 15 is set forth a plan of utilizing in connection with railway tracks and cars, pictorial or geographical representations spread over the surface of the base upon which said tracks are laid to cause the cars to travel 20 through or past such representations in a predetermined course.

Necessarily in a device such as above outlined, the tracks are quite small, the curvatures and bends of the track rails in instances relatively sharp or abrupt, and the cars are at times too light in weight to overcome the usual tendency thereof to jump the rails, especially when under speedy propulsion.

30 With the foregoing in mind, it is the primary object of the present invention to provide improved means coöperating with the cars and tracks to maintain the cars on their rails throughout the entire travel thereof, and to this advantageous end, the preferred embodiment of the invention comprehends the furnishing of the car with a pair of shoes, or equivalent devices, adapted to engage the under surface of the tread portions of the rails whenever the tendencies of the car is to leave the rails and thus overcome such tendency, consequently retaining the car in normal operative position. Conveniently this embodiment of the invention 45 embraces instrumentalities carrying said shoes in a manner permitting the ready introduction of the shoes beneath the rails, and removal thereof away from association with the rails when it may be the desire or necessity to bodily remove the car for storage as in shipping, for purposes of repair, &c.

The details of the construction and arrangement of parts will be apparent from the specific description hereinafter given, 50 when considered in connection with the accompanying drawings forming part hereof,

and wherein several embodiments of the invention are illustrated.

In the drawings: Figure 1 is a plan view of the base portion of my improved device; Fig. 2 is a vertical section through the same, and a car thereon; Fig. 3 is an enlarged sectional view of the means for retaining the car on its track, and, Fig. 4 is a similar view of a somewhat modified construction.

60 In the drawings, wherein like reference characters designate corresponding parts in the several views, and first with particular reference to Figs. 1, 2 and 3, A represents a base, or what may properly be styled a roadbed, the same being of any suitable outline, preferably formed of square sections *a*, designed to be separated for packing, &c., and secured in adjoining positions to constitute a completed whole by any convenient fastening devices, indicated at B.

65 In my prior structure above noted, I formed the base of wood bearing a surface of plastic molded in keeping with the topography intended to be depicted thereby, but as an improvement over such idea, the base sections here are pressed from sheet metal so that the same may be formed of a single sheet while similarly presenting topographical formations where desired or expedient, 70 represented in a general way at C.

75 The sheet metal base sections are grooved, as at D, to provide what may be called the roadbed, said grooves following the circuitous path to be traveled by the cars and 80 having vertical side walls E arranged at a distance apart somewhat greater than the distance between the car wheels F supporting the car body, represented at G. The purpose of these vertical side walls E is to 85 fasten and support the track rails H thereagainst, said rails having vertical webs *h* lying parallel to said walls, and within the grooves D, and secured to the walls by riveting, or otherwise *h'*. These rails are preferably of sheet metal, bent inwardly, thence outwardly to constitute the tread portions of the rails as shown, said tread representing approximately one half the conventional railroad rail, and the tread in the present 90 instance overhanging the outer portions of the grooves D, for reasons to presently appear.

95 To prevent the car jumping the rails, the same carries a pair, or several pairs, of retaining shoes, the same being rounded both longitudinally and transversely on their

upper face, and arranged normally directly beneath the tread portion of the rails H, in position to engage the latter should the car tend to leave said rails, thereby overcoming such tendency and maintaining the car in constant operative association with the rails.

The shoes J are mounted on downwardly bowed offset extensions K, of upright bars L supported from the car G by being 10 slidably mounted upon a cross rod M having squared ends m fastened in the opposite side walls of the car, an expansion spring N sleeved upon said rod thrusting the bars L outwardly, and nuts O threaded upon the 15 rods outside the bars adjustably limiting the separation of said bars and consequently the separation of the shoes J.

The upper ends of the bars L indicated at P are turned outwardly and passed 20 through the side walls of the car at p, and provided with knobs Q or the like adapted to be engaged by the thumb and finger of an operator to press the bars inwardly toward each other, against the force of the spring 25 N, to correspondingly carry the shoes J away from below the rail treads, and permitting withdrawal of the shoes through the opening, intermediate of the opposite rails when the car is lifted from the track, 30 as will be obvious.

The two-point bearing afforded by sleeving the bars L upon the rod M, and the protruding of their upper ends through the car walls at p will effectually prevent any 35 rocking of the bars longitudinally of the cars, while permitting the intended sliding movement thereof over the cross-rod in the application or retraction of the shoes J, relative to the track rails.

40 The adjustment of the parts hereinafter defined is such that the shoes J do not engage the webs h of the rails, while said shoes occupy a position close enough to the treads of the rails to properly perform their car-retaining function without presenting normally any appreciable frictional-retarding contact between the shoes and said treads.

45 In the device thus far described, the retaining mechanism, although located close to the wheels of the car, are offset slightly with reference to said wheels, in the direction of travel of the car, so as not to have the flanges of the wheels in the path of movement of the shoes in the application or withdrawal of the same. However, in some instances, it is desirable to have the retaining shoes directly below the peripheral bearing point of the wheels, to insure against 50 canting of the car lengthwise of the rails, and to this end I have suggested that embodiment of my invention illustrated in the remaining view of the drawings, to wit, Fig. 4. Here I present a structure involv-

ing a retainer mechanism capable not only 65 of an inward movement in the withdrawing operation, but also of a downward movement to escape the flange of the traction wheel; the same being accomplished by supporting the retaining shoes R upon downwardly-bowed lower ends S of crossed-levers T pivotally mounted upon the car through the medium of a pivot pin U, the lower portions of the lever and the shoes being thrust apart normally, by a spring V 75 interposed between the upper portions of the levers and carried by a concentric rod W pivoted to one of said upper portions and at its threaded end passing freely through the other to be engaged by an adjustable nut 80 X limiting the spreading of the levers and incidentally fixing the relative positions of the shoes R.

The upper outer ends of the levers T project through slots Y in the sides of the car 85 and are provided with knobs Z similar to and for the same purpose as the knobs Q hereinbefore described.

90 While I have herein pointed out two embodiments of the invention, it will be understood by persons skilled in the art that said invention is capable of embodiment in still other forms and devices as may be in keeping with the hereto appended claims.

I will not claim herein the derailment device inasmuch as the same more properly constitutes subject matter for a divisional application.

Having thus described the invention, what is claimed is:

1. In a toy railroad, a base supporting suitable track members, said base having topographical representations bordering the track members formed by integral portions of said base.

105 2. In a toy railroad, a base supporting suitable track members, said base having topographical representations bordering the track members formed by integral portions of said base, the base being of sheet metal, 110 and said integral portions being pressed therefrom.

115 3. In a toy railroad, a sectional base supporting suitable track members, said base having topographical representations bordering the track members formed by integral portions of said base.

120 4. In a toy railroad, a sectional base supporting suitable track members, said base having topographical representations bordering the track members formed by integral portions of said base, the base being of sheet metal, and said integral portions being pressed therefrom.

125 5. In a toy railroad, a base formed with integral depressed portions constituting a road bed having parallel side walls, of track members laid in said depressed portions and

having web portions lying directly against said side walls, in combination with means for securing the track members and side walls in said engaging relation, substantially as described.

6. In a toy railroad, a base formed with grooves constituting a roadbed, track members laid in said grooves and connected to the opposite side walls of the grooves.

10 7. In a toy railroad, a sheet metal base formed with integral grooved portions constituting a roadbed, and track members laid in said grooved portions and connected to the opposite side walls of the grooved portions.

15 8. In a toy railroad, a base formed with grooves constituting a roadbed, track members laid in said grooves and fastened to the opposite side walls of the grooves, the track members comprising rails having web portions lying against said side walls and tread portions offset therefrom.

20 9. In a toy railroad, a sheet metal base formed with integral grooved portions constituting a roadbed, track members laid in the grooved portions and fastened to the opposite side walls of the grooved portions, the track members comprising rails having web portions lying against said side walls

30 and tread portions offset therefrom.

10. In a toy railroad, a base formed with grooves constituting a roadbed, track members laid in said grooves and fastened to the opposite side walls of the grooves, the track members comprising rails having web portions lying against said side walls, and tread portions offset therefrom by bending the web portions inwardly and thence outwardly, substantially as described.

40 11. In a toy railroad, a sheet metal base formed with integral grooved portions constituting a roadbed, track members laid in the grooved portions and fastened to the opposite side walls of the grooved portions, the

45 track members comprising rails having web portions lying against said side walls, and tread portions offset therefrom by bending the web portions inwardly and thence outwardly, substantially as described.

50 12. In a toy railroad, a base formed with integral depressed portions constituting a

roadbed, and track members laid in said depressed portions, the tread portions of said track members being substantially flush with the adjoining upper surface of the base.

13. In a toy railroad, a base formed with integral depressed portions constituting a roadbed, and track members laid in said depressed portions, the tread portions of said track members being substantially flush with the adjoining upper surface of the base, and fastening means between the base and track members located below the said upper surface of the base.

65 14. In a toy railroad, a base formed with grooves constituting a roadbed, and track members laid in said grooves, and fastening means between a wall of the grooved portions and the track members.

70 15. In a toy railroad, a base formed with grooves constituting a roadbed, track members laid in said grooves, and fastening means between portions of the grooved portions and the track members located below the upper surface of the base.

75 16. In a toy railroad, a base formed with grooves constituting a roadbed, and track members laid in said grooves substantially coextensive therewith.

80 17. In a toy railway, a base formed with grooves constituting a roadbed, track members laid in said grooves in pairs, one adjacent each side wall of the grooved portions, and each track member having an inwardly-turned tread flange, substantially as described.

85 18. In a toy railway, a base formed with grooves constituting a roadbed, track members laid in said grooves in pairs, one adjacent each side wall of the grooved portions, and each track member having an inwardly-turned tread flange overhanging unobstructed spaces therebelow, substantially as described.

90 In testimony whereof I hereunto affix my signature in the presence of two witnesses.

THOMAS CARL SPELLING.

F. FRIEDLING.

Correction in Letters Patent No. 1,110,655.

It is hereby certified that in Letters Patent No. 1,110,655, granted September 15, 1914, upon the application of Thomas Carl Spelling, of New York, N. Y., for an improvement in "Toy Railroads," an error appears in the printed specification requiring correction as follows: Page 1, line 76, strike out the comma, words, and reference-letter "indicated at B"; and that the said Letters Patent should be read with this correction therein that the same may conform to the record of the case in the Patent Office.

Signed and sealed this 20th day of October, A. D., 1914.
